PROCESS FOR THE PRODUCTION OF ROLLED
AND STAMPED TABLE AND KITCHEN
ARTICLESPeter Bosbach and Emil Keller, Hildern,
Rhineland, GermanyApplication November 6, 1937, Serial No. 173,176
In Germany November 13, 1938

1 Claim. (Cl. 76—105)

The present invention relates to processes for the production of rolled and stamped table and kitchen articles, particularly spoons, made of iron, rustless steel, alpacca and aluminium. In the production of articles of this kind, for example spoons, according to the hitherto known processes, preliminary workpieces or patterns are first stamped out of the work material. In these workpieces the handle part is already preformed whilst the scoop or similar part consists of a rectangular lug which is only of small breadth but which corresponds in its length approximately to the length of the scoop part of the article. Then the said lug is rolled out in the direction of its breadth until it is somewhat greater in its length and breadth than the flattened-out scoop part would be. After the rolling operation the shape of the scoop part is stamped out and the scoop part is then flanged by means of presses in known manner. Inasmuch as the material used for the production of the preliminary workpieces is of the same thickness at all parts, there is formed, during the rolling out of the scoop lug, a broad rectangle, the thickness of which is comparatively small but is the same at all parts. This has the disadvantage that in the finished flanged scoop part the tip and the rims of the said part become very thin and also sharp. As a result of this the appearance of the finished spoon is very much depreciated, inasmuch as even when high priced work material is employed the impression of inferiority is produced. Furthermore, the known process has the disadvantage that in stamping out the flattened scoop part from the rolled scoop lug, a fairly considerable amount of waste is produced, the value of which is very small inasmuch as, for example, rustless steel waste is not willingly taken back by the raw material factories.

In order to economise material in the manufacture of spoons, it has already been proposed to produce the spoons by rolling, pressing, drawing and hammering from a cut-off piece of a round rod of the material in question. Even though in this manner it may be possible to lessen the quantity of waste, still at the same time the much more difficult process of manufacture gives rise to such high costs that the result is the opposite of an economy.

It has further already been proposed to produce the scoop part of the spoon by pressing instead of by rolling, and for this purpose to give the lug of the scoop part, during the stamping operation, the preliminary shape which the said part is to have later on. In this process at least

one of the tools serving for the final pressing operation is so shaped that the finished scoop part exhibits thickened edges. This process has, however, the disadvantage that for the finishing of the scoop part of the spoon, it is necessary to employ a number of tools, with which the scoop part is gradually pressed out into its final size, and, besides this, a considerable expenditure of power is necessary for the pressing operation.

According to the invention it is proposed to eliminate the defects set forth above by providing a process wherein the lug for the scoop part is rolled out transversely to its longitudinal direction in such manner that it acquires an unequal thickness in its longitudinal direction and that thereby a thickening of the tip and the handle end is effected. Preferably the lug for the scoop part, which has been rolled in its longitudinal direction, is at the same time given a variable thickness in the transverse direction, whereby the rims of the scoop part are thickened.

As a consequence of this construction the spoons produced according to the novel process are particularly good in respect to their shape and applicability. By the new rolling process, a broad uniformly thick rectangular lug which yields considerable waste during the cutting out of the scoop part is not, as hitherto, produced, but, on the other hand, the lug for the scoop part rolled according to the novel process exhibits a close approximation to the profile of the scoop part which is to be stamped out of it, so that only very little waste is produced. At the same time, moreover, by the rolling operation the tip of the scoop part and also the handle end thereof are gradually increasingly thickened. Furthermore the lug for the scoop part may advantageously be also rolled out in such manner that it is of different thicknesses in the transverse direction, so that the edges of the said part are somewhat thickened. The succeeding trimming operation imparts a very nice shape to the said scoop part, inasmuch as the edges are no longer thin and sharp, but exhibit over the whole oval of the part an increased thickness which increases somewhat towards the tip and the handle end and is agreeable in use.

A preferred method of applying the invention in practice is illustrated by way of example in the accompanying drawing, in which:

Fig. 1 is a plan of a preliminary workpiece or pattern,

Fig. 2 is a plan of a pattern with the lug for the scoop part rolled out,

Fig. 3 is a side view of Fig. 2.

Fig. 4 shows a finished spoon in plan, and Fig. 5 shows a cross section through the scoop part taken on the line A—A of Fig. 2.

Referring to the drawing:

- 5 For the production of spoons of iron, alpacca, aluminium or rustless steel, the work material is cut into strips out of which the preliminary workpieces or patterns are stamped. During the operation of stamping out of the patterns the 10 handle *a* is at once given its final form in the direction of its width, whereas the scoop part *b* consists of a narrow rectangular lug the length of which corresponds approximately to the finished scoop part. After the stamping operation 15 the rolling of the lug *b* for the scoop part is carried out transversely to its longitudinal direction. By the new method of rolling, the lug for the scoop part is not, as hitherto, rolled out into a broad rectangle (as indicated in chain 20 dotted lines in Fig. 2), but its shape approximates more closely to that of the scoop part in its final form. The rolling operation is carried out in such manner that the lug for the scoop part retains in proximity to the tip *c* and the handle 25 end *d* approximately the original thickness. At the same time, however, it is possible to carry out the transverse rolling operation, if desired, in such manner that the thickness also gradually increases towards the edges *f* of the scoop part, 30 so that a cross section corresponding to that shown in Fig. 5 is obtained.

The waste which arises in the succeeding operation of stamping out the scoop part is very small, inasmuch as only the parts projecting beyond the shape indicated in long chain dotted lines have to be cut away (see Figs. 2 and 3). Then the scoop part is brought into its final form by a trimming operation and the handle

is also shaped out and bent. During this operation, by suitable rolling, the tip and also, if desired, the edge of the spoon can be shaped to a curved form. After any desired decorative working operations have been carried out the 5 spoon is then ready for sending out.

It is, of course, to be understood that the invention is not restricted to the example illustrated but that many other constructional forms and modifications are possible. Thus, for example, the process might also be employed in the production of spoons having a circular scoop part, basting spoons or other table or kitchen articles, the edges of which are subjected to particularly great wear.

15

We claim:

In a method of manufacturing blanks for table and kitchen articles, particularly spoons made of iron, rustless steel, alpacca, aluminium and similar materials, the steps of: stamping out of 20 preliminary workpiece such that the handle portion receives its final form in the direction of its width and the scoop portion receives the form of a narrow lug having substantially the length of the finished scoop part; and then subjecting 25 the said scoop portion to a rolling operation transversely to its longitudinal direction and spreading the intermediate portion to a considerably greater extent than the end and the portion adjacent to the handle, so that the said 30 scoop portion is given a thickness which increases longitudinally and transversely from the intermediate portion of the scoop towards the tip and handle ends and towards the sides thereof, said tip and handle ends retaining substantially their original thickness.
